Related U.S. Application Data

What is claimed is the ornamental design for a circle and
bi-directional ray drawing device, as shown and described
herein.

(63) Continuation of application No. 29/256,181, filed on
Mar. 15, 2006, now Pat. No. Des. 557,623.

(51) **LOC (8) CI.** **10-04**

DESCRIPTION

(52) **U.S. CL.** **D10/65**

FIG. 1 is an elevated, perspective view of the circle and
bi-directional ray drawing device, which includes a 360°
protractor pivotally connected to a pair of radius arms;
FIG. 2 is a top plan view of the embodiment shown in FIG.
1;

(58) **Field of Classification Search** D10/65;
33/27.01, 27.031, 27.032, 27.033, 465, 468,
33/471, 534, 538, 481, 485, 489, 678, 666,
33/1 AP, 1 N

FIG. 3 is a bottom plan view of the embodiment shown in
FIG. 1;

See application file for complete search history.

FIG. 4 is a right side edge view taken perpendicularly with
respect to the radius arms of FIG. 1;

(56) **References Cited**

FIG. 5 is an upper edge view of the embodiment shown in
FIG. 1 taken perpendicular to the view of FIG. 4;

U.S. PATENT DOCUMENTS

FIG. 6 is a lower edge view of the embodiment shown in
FIG. 1 taken perpendicular to the view of FIG. 4; and,

FIG. 7 is a left side edge view taken perpendicularly with
respect to the radius arms of FIG. 1.

The thicknesses shown in FIGS. 1, 4, 5, 6, and 7 of the disk
and the radius arm are not necessarily to scale, due to line
thicknesses and/or other illustration limitations. Typically,
the thicknesses of these layers will each be less than about
1 centimeter, with no relative thicknesses being implied by
the drawings. Additionally, certain design features are
shown in phantom or broken lines for illustrative purposes
only, thereby forming no part of this claimed invention.
